UNITED STATES PATENT OFFICE.

MICHAEL C. REGAN, OF WASHINGTON, DISTRICT OF COLUMBIA.

PORTABLE SAFE.

1,395,771.

Specification of Letters Patent.

Patented Nov. 1, 1921.

Application filed September 8, 1920. Serial No. 408,838.

To all whom it may concern:

Be it known that MICHAEL C. REGAN, a citizen of the United States of America, residing at Washington, District of Columbia, 5 has invented certain new and useful Improvements in Portable Safes, of which the following is a specification.

The object of my invention is to provide a simply constructed portable safe or container for holding stocks and bonds or other negotiable paper.

Another object of my invention is to provide means whereby upon the surreptitious opening of or tampering with the container, 15 the bonds or documents therein will be automatically marked with a number or other mark of identification which will either render the same non negotiable or make it readily apparent that they have been tampered with.

Other and further objects of my invention will be in part apparent and in part described as the specification is proceeded with.

In the accompanying drawings forming 25 part of this specification:

Figure 1 is a perspective view of the safe or container;

Fig. 2 is a sectional view through the safe or container showing the marker in 30 place;

Fig. 3 is a sectional view of one of the containers partly broken away to show the grooved or channeled walls;

Fig. 4 is a section on the line 4—4 of 35 Fig. 1;

Fig. 5 is a section on the line 5—5 of Fig. 1;

Fig. 6 is a perspective view of the stencil pad partly broken away to show the chemical 40 containing channels or grooves; and

Fig. 7 is a modified form of stencil pad, and

Fig. 8 is a fragmentary side elevation of the locking mechanism.

Referring more particularly to the drawings wherein like reference numerals refer 45 to corresponding parts throughout the several views 1 denotes the upper end 2 the lower half of a double walled portable safe or container 3, preferably made of sheet steel or equally strong material, adapted to be slidably received within an outer locking container or housing 4, the construction and operation of which will be presently described in detail.

55 The container 3 is preferably rectangular in shape and is formed of outer and inner

shells or walls 5 and 6 having a net work of communicating channels 7 therebetween formed by grooving or channeling the outer wall or shell 5 on its inner face, which channels are filled with suitable explosive chemical 8. The locking container or housing 4 is similarly constructed, that is, comprises outer and inner shells or walls 9 and 10, the former being grooved on its inner face as at 11 to 60 receive an explosive chemical 12 the purpose of which will be described hereinafter.

Suitably secured within the container 3 are oppositely disposed pairs of narrow spring metal rack plates or bands 13 and 14 65 formed with transverse ledges or corrugations. The bonds or other documents 15 are placed in the container 3 with their side edges engaged between the corrugations of the rack plates 13 and 14 in the following 70 manner: First a paper such as a bond, currency or the like 15 is inserted in place at the bottom of container 3, a marking or stencil pad or plate 16 is superposed thereon and then two bonds or papers placed upon 75 the marking plate and so on until the container is filled, it being understood that there may be at least two bonds to each stencil pad. These marking or stencil pads 16 are made up of an intermediate sheet 17 of 80 fiber board, asbestos or the like having letters or words cut therein forming grooves 18, in which a chemical substance 19 is placed. In the present instance the words cut in the sheet 17 will when reproduced 85 on the bonds or other papers 15 indicate that the latter have been tampered with. Preferably the chemical substance 19 will be 90 protected by a thin coating of shellac or the like and on each side of the intermediate 95 sheet 17 is placed a thin steel plate 20 having grooves or letters cut therefrom corresponding to and registering with the letters or grooves 18 in the plate 17.

Surreptitious withdrawal of the bonds or 100 papers 15 from between the stencil pads 16 is prevented by means of oppositely disposed sharp pointed lugs or projections 21 formed by cutting or slitting the plates and bending the slitted portions slightly outwardly. Any attempt to withdraw the bonds or papers from between adjacent pads 16 as where a messenger succeeds in cutting through the container walls, will result in 105 tearing the papers in an obvious manner.

The pads 16 are formed with lateral extensions 22 corresponding to the extensions 110

23 on the intermediate sheet 17 said extensions being adapted to enter the centrally disposed grooves 24 in the sides of the container 3 forming part of the net work of 5 grooves 7 thus preventing the withdrawal of the pads 16 except by lifting them vertically out of the grooves. It will be understood that the ends of the stencil pads 16 will fit within the corrugations of the rack plates 10 13 and 14 and due to the rigidity of the pads the bonds or other papers can be compactly retained in the container 3. If desirable a clamping member 33 may be employed for securely holding the documents 15 in place. 15 This member comprises top and bottom metallic plates 34 and 35 with a suitable chemical substance 36 therebetween adapted to communicate with a similar chemical substance 37 in grooves 38 formed in the side 20 walls of the container 3.

In Fig. 7, I have described a modified form of stencil pad comprising metallic plates 39 and 40 having registering openings, such as letters 41 cut therefrom. Interposed between 25 these plates is a fabric sheet 42 impregnated with a marking fluid such as ink the purpose of which will be described hereinafter.

The container 3 slidably fits within the opening 34 in the locking container or housing 4 and is retained therein by means of a pair of arms 25 and 26 pivoted to the inner walls of the outer container 4 as at 27 and 28. These arms carry disks or the like 29 and 30 at one end thereof adapted to normally seat in correspondingly shaped recesses 31 and 32 formed in the walls of the inner container 3 when the latter is inserted in the outer or locking container.

The locking and unlocking operation is effected by any suitable locking mechanism, 40 preferably that described and claimed in my copending application Serial No. 408,837, filed Sept. 8, 1920, and which may be very briefly described as follows: A plunger 43 is slidably mounted in a cylinder 44 carried by a casting 45 in turn mounted in the extended end 46 of the container or housing 4. This plunger is connected at its outer end with an operating knob or button 47 and at 45 the other end carries oppositely disposed beveled lugs 48 and 49 adapted to engage corresponding lugs 50 and 51 formed on enlargements 31 and 32 on the ends of the arms 25 and 26 opposite to the ends which carry the disks 29 and 30, this operation being effected by pushing the plunger 43 inwardly. As the plunger is pushed inwardly lugs 53 and 63 carried thereby which normally rest beneath the lugs 50 and 51 and maintain the 55 arms 25 and 26 in locked position, are also moved inwardly thus permitting the lugs 48 and 49 to engage the lugs 50 and 51 to rock the arms to inoperative or unlocked position. Springs 54 and 55 also serve to support the 60 enlargements of the arms in an obvious man-

ner. It is understood that the plunger 43 is controlled by suitable locking mechanism (not shown) such as disclosed in my application heretofore mentioned.

If desired a key locking and unlocking mechanism may be employed comprising a cylinder 56 having a key hole not shown in which a key (also not shown) is adapted to enter. As the key is pushed home it forces the hooked shaped finger 57 carried by the plunger 58 into engagement with the spiral slot 59 formed in the end of the plunger 43, thus drawing the lugs 48, 49 into engagement with the lugs 50, 51 against the tension of spring 60, thereby releasing the grip of 80 the spring arms on the container 3 in an obvious manner.

Should an attempt be made to open the containers by drilling or cutting the chemical substance contained between the walls of 85 the containers and elsewhere will be ignited by friction, it being understood that some chemical having the property of fulminate of mercury or friction match head paste will be used. The chemical used will preferably 90 be mixed with steel wool to increase the friction when drilled into and will also preferably contain a chemical which will ignite when brought into contact with water. Hence any unauthorized attempt to reach 95 the interior of the containers will cause the chemicals to burn and such fire will quickly spread via the net work of grooves to the extensions or lugs 22 and 23 of the marking pads and thence to the grooves 18 and chemicals therein. It will be obvious that the letters, numbers or other characters or words cut in the marking pads will be reproduced by burning or scorching the same upon the 100 papers or documents therebetween. However the steel plates 20 effectually prevent the scorching or burning of the entire paper or document. The area of the document 105 which it is desired to mark or burn may of course vary.

Where the modified form of marking pad illustrated in Fig. 7 is employed the expansion of the gas given off by the burning chemical is relied upon to cause the ink with which the fabric sheet 42 is saturated, 110 to flow through the grooves 41 into the bonds 15 thereby sufficiently marking the latter to greatly facilitate the detection of their theft should an attempt be made to dispose of the same. If water is introduced to the interior 115 of the containers in an attempt to destroy the chemicals therein, this will have the same effect as drilling or cutting into the chemicals.

Having thus described my invention what 125 I claim is:

1. A portable safe comprising a housing having an opening extending therethrough, a container adapted to be slidably inserted in said opening, and project therethrough, 130

said container having openings in its top and bottom walls intermediate the ends thereof, and spring arms pivotally carried on said housing having enlargements adapted to enter said openings for locking said container in said housing, and means for releasing said enlargements from said openings.

2. A safe comprising a container, the walls of said container being provided with a net work of grooves, a chemical substance in said grooves adapted to be ignited by friction, and means for holding papers in stacked relation in communication with said grooves whereby when said walls are drilled said substance will ignite and the portions of said papers adjacent said grooves will be scorched.

3. A safe comprising a container, stencil

pads for holding papers therebetween, said pads having cut away portions adapted to expose a portion of the said papers, and chemical substance positioned on the interior of said container adapted to ignite by friction, whereby said substance will ignite and the exposed portion of said papers will be marked upon the puncturing of the walls of said container with a mark corresponding to the configuration of said cut away portions.

4. In a safe for holding papers, means for holding said papers in stacked relation, plates inserted between opposing papers having oppositely extending projections, whereby the withdrawal of said papers from between said plates will cause said papers to be mutilated.

In testimony whereof I affix my signature.

MICHAEL C. REGAN.
